US00D542016S

(12) **United States Design Patent** (10) **Patent No.:** **US D542,016 S**
Teteriatnikov (45) **Date of Patent:** **** May 8, 2007**

- (54) **COMBINED SHOE BOTTOM AND PERIPHERY**
(75) Inventor: **Savva Teteriatnikov**, Hermosa Beach, CA (US)
(73) Assignee: **Skechers U.S.A., Inc. II**, Manhattan Beach, CA (US)
(**) Term: **14 Years**
(21) Appl. No.: **29/248,911**
(22) Filed: **Sep. 8, 2006**
(51) LOC (8) Cl. **02-04**
(52) U.S. Cl. **D2/953; D2/947; D2/951**
(58) **Field of Classification Search** .... **D2/902, D2/946-949, 951-960; 36/3 B, 22 R, 24.5, 36/25 R, 28, 32 R, 34 R, 67 A, 59 C**

(57) **CLAIM**

The ornamental design for a combined shoe bottom and periphery, as shown and described.

DESCRIPTION

FIG. 1 is a perspective view of a combined shoe bottom and periphery in accordance with my new design;
FIG. 2 is a bottom plan view thereof;
FIG. 3 is a left side elevational view thereof;
FIG. 4 is a right side elevational view thereof;
FIG. 5 is a front elevational view thereof; and,
FIG. 6 is a rear elevational view thereof.
Broken lines in the figures are for illustrative purposes only and form no part of the claimed invention.
